J. KAUFMANN

PILE FORMING WIRE FOR PILE FABRIC LOOMS

Filed July 7, 1922

Inventor
Jacob Kaufmann,
By Jas. C. Nobensmith
Attorney.

UNITED STATES PATENT OFFICE.

JACOB KAUFMANN, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

PILE-FORMING WIRE FOR PILE-FABRIC LOOMS.

Application filed July 7, 1922. Serial No. 573,371.

To all whom it may concern:

Be it known that I, JACOB KAUFMANN, a citizen of the United States, residing at Philadelphia, in the county of Philadelphia and State of Pennsylvania, have invented certain new and useful Improvements in Pile-Forming Wires for Pile-Fabric Looms, of which the following is a specification.

My invention relates to pile forming wires for pile fabric looms of the type wherein a plurality of the pile forming wires extend through the reed in a direction parallel to the warp threads and which are so arranged as to be controlled by means of heddles to which the wires are pivotally connected, this arrangement being provided for the purpose of forming patterns of the piles or loops in the fabric.

The principal object of my invention is to provide a novel form of pile forming wire and controlling heddle which will be simple in construction and efficient for its intended purpose, which will be characterized by the absence of projecting parts on the side surfaces of the heddle whereby the warp threads may freely pass without interference during the formation of the sheds, and which is further characterized by the provision of a large bearing surface for the pivotal connection between the pile forming wire and its controlling heddle.

The nature and characteristic features of my invention will be more readily understood from the following description, taken in connection with the accompanying drawings forming part hereof, in which

Figure 1 is a side elevation of a pile forming wire, and its controlling heddle, embodying the main features of my present invention;

Fig. 2 is a fragmentary perspective view, greatly enlarged, of the pivotal portion of the pile forming wire and its controlling heddle;

Fig. 3 is a horizontal section thereof, taken approximately on the line 3-3 of Fig. 2;

Fig. 4 is an elevational view of one end of the controlling heddle illustrating the interlacing of the ends of the pair of members of which the heddle is composed;

Fig. 5 is a vertical section thereof, taken approximately on the line 5-5 of Fig. 4; and

Fig. 6 is a perspective view thereof.

Referring to the drawings, in the particular embodiment of my invention therein shown, 10 is the pile forming wire proper, upon the free end portion 11 of which the pile or loop is formed, in the manner well understood by those skilled in the art. In some instances the upper marginal edge of the enlarged portion 11, at the end thereof, is sharpened for the purpose of forming a cut pile fabric which alternative arrangement is also well known to those skilled in the art.

The other end of the pile forming wire 10 is pivoted, as at 13, to the controlling heddle 14, which comprises a pair of flat, thin strips of metal 15, arranged side by side with the pivotal end of the pile forming wire 10 disposed therebetween. At the place of the pivotal attachment of the pile forming wire 10 to the controlling heddle 14, each of the thin, flat strips of metal or wire 15 comprising said heddle 14 is provided with a boss 16 extending inwardly (See Fig. 3), the inner surfaces of the bosses 16 abutting against each other to thereby form a relatively large pivot for the aperture 17 at the end of the pile forming wire 10. The bosses 16 are formed in the flat strips or wires 15 by forming the metal inward, so that there is thereby left a depression 18 in the outer surface of each of the strips 15. The bosses 16 are centrally perforated for the passage of a rivet 19, the heads 20 of which are positioned within the depressions 18 in the outer surfaces of the strips 15, as above mentioned, so that there will be no parts projecting beyond the outer surfaces of the strips 15.

The ends of the strips 15 are provided with suitable mortises for mounting the same in the harness frames of the loom. The ends of the strips 15 are preferably interlaced by making the mortise 21 of one strip longer than the mortise 22 of the other strip and of sufficient width to permit the other strip to pass therethrough, as illustrated in Figs. 4, 5 and 6 of the drawings.

By the foregoing arrangement, there will be provided a pile forming wire and heddle for controlling the same in which the pivotal connection between the pile forming wire proper and its supporting heddle will be simple in construction, yet efficient for

- its intended purpose, being characterized by the absence of projecting parts on the side surfaces of the strips comprising the heddle, which projections would interfere with the free passage of the warp threads as the sheds are successively formed, the pivotal action being at all times free and provided with a large bearing surface, thereby insuring less likelihood of destruction in use.
- Having thus described the nature and characteristic features of my invention, what I claim as new and desire to secure by Letters Patent is:
1. A pile forming wire, and a controlling heddle to which one end of said pile forming wire is pivotally connected, said heddle comprising two strips of thin, flat metal or wire having the pivotal end of the pile forming wire disposed therebetween, each of said strips having the metal stamped or pressed inward to form a boss, said bosses coacting to form a pivot for the end of the pile forming wire.
  2. A pile forming wire, and a controlling heddle to which one end of said pile forming wire is pivotally connected, said heddle comprising two strips of thin, flat metal or wire having the pivotal end of the pile forming wire disposed therebetween, each of said strips having the metal stamped or pressed inward to form a boss, said bosses coacting to form a pivot for the end of the pile forming wire, said bosses being centrally apertured, and a rivet passing through the apertures in said bosses for securing the same to each other.
  3. A pile forming wire, and a controlling heddle to which one end of said pile forming wire is pivotally connected, said heddle comprising two strips of thin, flat metal or wire having the pivotal end of the pile forming wire disposed therebetween, each of said strips having the metal stamped or pressed inward to form a boss, said bosses coacting to form a pivot for the end of the pile forming wire.

ing wire, said bosses being centrally apertured, a rivet passing through the apertures in said bosses for securing the same to each other, the heads of said rivet being positioned within the depressed portions in the outer surfaces of the strips comprising the heddle.

4. A pile forming wire, and a controlling heddle to which one end of said pile forming wire is pivotally connected, said heddle comprising two strips of thin, flat metal or wire having the pivotal end of the pile forming wire disposed therebetween, each of said strips having the metal stamped or pressed inward to form a boss, said bosses coacting to form a pivot for the end of the pile forming wire, said bosses being centrally apertured, a rivet passing therethrough, the heads of said rivet being positioned within the depressed portions in the outer surfaces of the strips comprising the heddle, and the ends of the strips comprising the heddle being interlaced.

5. A pile forming wire, and a controlling heddle to which one end of said pile forming wire is pivotally connected, said heddle comprising two strips of thin, flat metal or wire having the pivotal end of the pile forming wire disposed therebetween, each of said strips having the metal stamped or pressed inward to form a boss, said bosses coacting to form a pivot for the end of the pile forming wire, said bosses being centrally apertured, a rivet passing therethrough, the heads of said rivet being positioned within the depressed portions in the outer surfaces of the strips comprising the heddle, and the ends of the strips comprising the heddle being provided with mortises, one of said mortises being of greater extent and the end of the other strip being interlaced therethrough.

In testimony whereof, I have hereunto signed my name.

JACOB KAUFMANN.
